UNITED STATES PATENT OFFICE.

DE WANE B. SMITH, OF DEERFIELD, ASSIGNOR OF ONE-HALF TO CHARLES H. POOLE, OF UTICA, NEW YORK.

HARNESS.

SPECIFICATION forming part of Letters Patent No. 444,401, dated January 6, 1891.

Application filed February 28, 1890. Serial No. 342,129. (No model.)

To all whom it may concern:

Be it known that I, DE WANE B. SMITH, of Deerfield, in the county of Oneida, in the State of New York, have invented new and useful 5 Improvements in Harness, of which the following, taken in connection with the accompanying drawings, is a full, clear, and exact description.

My invention relates to improved harness, 10 and has for its object the production of a simple and effective device which is operatively placed on the horse with far greater ease than devices of this character heretofore produced, is economically manufactured, and is durable 15 and effective in use and pleasing in appearance; and to this end the invention consists, essentially, in a draw or cross bar imposed beneath the horses and outer metallic traces loosely connected to the opposite extremities 20 of said bar and loosely connected at their forward extremity to the hame or collar.

The invention also consists in securing a strap to the said cross-bar between the same and the horse, in composing the said bar 25 of separable halves, whereby a team may be harnessed singly, single whiffletrees secured to the separate extremities of the draw or cross bar, inner traces connected to the adjacent extremities of said whiffletrees and 30 to the separate hames or collars, and a double whiffletree connected to the said single whiffletrees.

The invention still furthermore consists in the detail construction and arrangement of 35 the parts, all as hereinafter more particularly described, and pointed out in the claims.

In describing this invention reference is had to the accompanying drawings, forming 40 a part thereof, in which like letters indicate corresponding parts in all the views.

Figure 1 represents a perspective of a team of horses having my harness operatively placed thereon. Fig. 2 represents a top plan view of the detached harness with the hames shown 45 partly in perspective for the purpose of illustrating their connection to the traces of my harness. Fig. 3 represents an edge view of the parts as illustrated in Fig. 2. Fig. 4 is an enlarged plan view of a detached half of 50 the harness; Fig. 5, a perspective of the detached adjacent extremities of the separable

divisions of the cross or draw bar. Fig. 6 is a longitudinal sectional view of the parts illustrated in Fig. 5, further illustrating the operation of the device or catch for securing 55 together the adjacent extremities of said draw or cross bar. Fig. 7 is a top plan view of a double whiffletree forming a part of my harness. Fig. 8 is a perspective of the detached outside trace of the harness, and Fig. 9 is a 60 plan view of a modified form of the inner traces.

A represents the draw or cross bar of my harness, composed of suitable material and bent in any desired form. As illustrated and 65 as preferably constructed, however, this bar is formed with a raised central portion a and depressed extremities connected to the outside traces B. This draw or cross bar A is preferably composed of separable halves or 70 divisions, whereby a team may be harnessed singly, and these divisions are secured together at their inner extremities by a catch C. As best seen in Fig. 5, one of said divisions is formed with a socket a' , in which the opposite 75 extremity a^2 is entered, and secured by the catch C, consisting of a sliding rod c, supported by a bracket a^3 , and having its lower end movable up and down in the slot a^4 and automatically forced to operative position by 80 a spring a^5 interposed between a shoulder a^6 formed upon said pin and the adjacent face of the bracket a^3 .

As presently described, the remaining parts of my harness form independent harnesses, 85 which may be separately placed upon a team either in their respective stalls or elsewhere, whereupon they may be brought together, and by simply pulling up the catch C and inserting the end a^2 of one division of the draw or 90 cross bar into the socket a' of the opposite division the separate halves of the harness are connected together. This is a feature of great advantage, since in harnesses of this character adapted for a team it is necessary to drive 95 the team to the desired position, and then walk them over the ordinary cross-bar, and if they are at all high-mettled they immediately prance around and render it extremely difficult and frequently dangerous to oper- 100 atively place said harnesses. Indeed, experience has demonstrated that frequently it is

necessary to have two attendants to secure a harness of this kind to a good lively team. On the other hand, by a draw-bar composed of separable divisions, the separate harnesses 5 may be assembled by a child upon the team singly at any desired time—as, for instance, when each is in its respective stall—and then when brought together by the operation of the catch C the separate harnesses are secured together, forming a double harness, thus effecting this desirable result without the slightest difficulty or danger and more quickly and conveniently than has heretofore been possible.

15 As seen in the drawings and as preferably constructed, the outer traces B are loosely connected at their forward extremities by interlocking links b to the respective hames D, and are formed with downwardly-deflected 20 rearward extremities B', pivoted or otherwise loosely connected at b' to the opposite extremities of the draw or cross bar A. It will thus be seen that the outside traces B B prevent the horses from swaying outwardly, and 25 by their loose connection to the draw or cross bar enable them to swing independently with the separate horses, whether they are keeping step or not. This is a feature of great advantage, since as a horse moves when under 30 way, there is considerable sway to his shoulder, and the trace thus compensates for this and transmits the pull to the draw or cross bar with a connection which yields with every movement, and thereby prevents any waste of 35 draft, as would result from a rigid connection. Moreover, it frequently happens that the horses do not keep step when pulling, and my improved harness is of especial value under 40 the circumstances, since the position of one trace does not affect in the slightest the position or operation of the other.

The harness is supported in position by a suitable saddle E, resting upon the horse, and connected by straps e, of suitable size and 45 construction, to either the said trace or the draw or cross bar, as may be desired. As illustrated, one of these straps is shown as connected to an eye e², supported by the trace B, and the other to an eye e³, supported by the 50 cross-bar A; but it will be understood that the said strap might be continued directly around the horse and then connected to any suitably-placed eye or other support.

In order to prevent rubbing of the horse by 55 the draw or cross bar A, which is preferably formed of metal, I place above said bar the lazy-strap F of suitable form, size, and construction and suitably supported upon the trace B and bar A, so that the horse rubs 60 against said strap instead of the bar A, and thus entirely obviates the injury which would otherwise result.

Suitably connected to the separate divisions of the cross or draw bar A are the single 65 whiffletrees G, which are illustrated as pivoted at their outer extremities g to a link g', pivoted at g² to the bar A. The inner ends

of said single whiffletrees are provided with suitable attaching-points g³, to which are attached the inner traces II, also preferably 70 flexibly connected to the respective hames D.

Secured to the respective single whiffletrees G by links or other flexible connections i is the double whiffletree I, to which is connected a chain or other suitable drawing means, (not 75 illustrated,) and adapted to be connected to a wagon or other article to be drawn.

When desired to separate the respective halves of my improved harness, as described, it is merely necessary to disengage one extremity of the double whiffletree from its connecting link, whereupon by means of the catch C the said harness is divided.

At Fig. 9 I have shown a modified form of inner trace composed of an endless rope or 85 chain K, loosely connected to the separate hames and passed back of a pulley k in the block K' in front of a pulley k', secured by a plate k² to the bar A, and back of a pulley k³, secured in the block, or a plate K'. The plate 90 K' is provided with a loop or other attaching means k⁴, to which a chain or other suitable drawing device is attached.

The operation of my invention will be readily perceived from the foregoing, and it will 95 be understood that the rigid outside traces prevent outward swaying of the horse when backing, &c., allow of or compensate for every movement when traveling, that the draw or cross bar enables the team to be harnessed singly with great ease and convenience, that the peculiar construction of single and double whiffletrees enables the harness to be composed of separable halves, and forms a simple and effective means of connecting the inner 100 trace to the draw-bar and the said bar to the article to be drawn. It will be understood, however, that considerable change may be made in the relative construction and arrangement of the parts of my invention without departing from the spirit thereof. Hence I 105 do not limit myself to its precise form and construction.

Having thus fully described my invention, what I claim as new, and desire to secure by 110 Letters Patent, is—

1. In combination with the traces and saddles of a double harness, the herein-described rigid cross or draw bar connected to said traces and saddles and composed of separable 115 divisions having their inner extremities approximated, and a movable catch for engaging said extremities and removably securing them together, whereby a team may be harnessed singly, substantially as and for the 120 purpose specified.

2. In combination with the traces and saddles of a double harness, the herein-described cross or draw bar connected to said traces and saddles and composed of separable divisions having their inner extremities approximated, and a spring-actuated sliding rod secured to 125 one of said divisions and removably engaging the other for removably securing together

said divisions, whereby a team may be harnessed singly, substantially as and for the purpose set forth.

3. In combination with the traces and saddles of a double harness, the herein-described cross or draw bar connected to said traces and saddles and composed of separable divisions, a socket provided on one of said divisions and adapted to receive the end of the other division, and a catch for removably securing said parts together, substantially as and for the purpose specified.

4. In combination with the traces and saddles of a double harness, a metallic cross or draw bar connected to said traces and saddles and adapted to be placed beneath the horse, and a strap above said metallic cross or draw bar adapted to be imposed between the horse and the said bar and having its opposite extremities secured to said cross-bar, substantially as and for the purpose specified.

5. In combination with the traces and saddles of a double harness, a metallic cross or draw bar connected to said traces and saddles and composed of separable divisions having their inner extremities removably secured together, whereby a team may be harnessed singly, and a strap above said cross or draw bar adapted to be imposed between the horse and said bar, substantially as and for the purpose set forth.

6. In a harness, the combination, with the collars, of a double harness, metallic traces loosely connected at their forward extremities to said collars, a cross or draw bar loosely pivoted to the rearward extremities of said traces, and a saddle for supporting said cross-bar, substantially as and for the purpose described.

7. In a harness, the combination, with a collar, a cross-bar, and a saddle for supporting said cross-bar, of a metallic trace having its forward end connected to said collar and having its rearward end deflected below the plane of its forward end, and laterally-extending arm provided on said rearward end and connected to said cross-bar, substantially as specified.

8. In combination with the collars and saddles of a double harness, the combination of 50 metallic traces loosely connected at their forward extremities to said collars, a cross or draw bar loosely connected to the opposite extremities of said traces and composed of separable divisions, and a catch for removably securing together said divisions, whereby a team may be harnessed singly, substantially as and for the purpose set forth.

9. The herein-described harness, composed of a pair of saddles and collars, a cross or draw bar connected to the saddles, outer metallic traces pivotally secured to said collars and cross-bar, single whiffletrees connected to said bar, and a double whiffletree connected to said single whiffletrees, substantially as 65 and for the purpose specified.

10. The herein-described harness, composed of a pair of collars and saddles, a cross or draw bar connected to said saddles, outer metallic traces pivotally connected to said cross-bar, single whiffletrees, links connecting the said whiffletrees and cross-bar, and a double whiffletree connected to the said single whiffletrees, substantially as and for the purpose set forth.

11. The herein-described harness, composed of a pair of collars and saddles, a cross or draw bar connected to said saddles and composed of separable divisions, and a catch for removably connecting said divisions, where- 80 by a team may be harnessed singly, outer metallic traces pivotally connected to said collars and to said bar, single whiffletrees, links between the said whiffletrees and cross-bar, and a double whiffletree connected to the said 85 single whiffletrees, substantially as and for the purpose set forth.

In testimony whereof I have hereunto signed my name, in the presence of two attesting witnesses, at Utica, in the county of Oneida, 90 in the State of New York, this 21st day of January, 1890.

DE WANE B. SMITH.
